UNITED STATES PATENT OFFICE.

JOHAN PARTMANN, OF NEW YORK, N. Y.

LOCK FOR HAND-BAGS.

1,072,981.

Specification of Letters Patent.

Patented Sept. 9, 1913.

Application filed March 11, 1913. Serial No. 753,590.

To all whom it may concern:

Be it known that I, JOHAN PARTMANN, a subject of the King of Hungary, and a resident of the city of New York, borough of the Bronx, in the county and State of New York, have invented a new and Improved Lock for Hand-Bags, of which the following is a full, clear, and exact description.

My invention has for its object to provide 10 a lock for hand bags which is operable by a trigger on the handle of the bag.

As the lock is constructed it is impossible to open the bag except by the operation of the trigger on the handle, which may be 15 covered by the hand used to carry the bag. For this reason pickpockets are unable to open the bag and remove the contents thereof in the manner in which these thieves are in the habit of working.

20 Additional objects of the invention will appear in the following complete specification, in which the preferred form of the invention is disclosed.

In the drawings similar characters of reference indicate corresponding parts in all 25 the views, in which—

Figure 1 is a side elevation of a portion of a bag, showing my improvement; Fig. 2 is an enlarged sectional view showing the 30 means for operating the lock; Fig. 3 is an enlarged sectional view showing how the lever is mounted which is used to connect the members disposed in the hollow handle and in the hollow rod; and Fig. 4 is a sectional view on the line 4—4 of Fig. 2; Fig. 35 5 is a sectional view on the line 5—5 of Fig. 3; and Fig. 6 is a sectional view on the line 6—6 of Fig. 1.

By referring to the drawings it will be 40 seen that the bag 10 has a mouth, at one side of which there is a frame member 11, which is normally disposed under the frame member 12, mounted on the other side of the bag 10. Disposed over the frame member 11 there is a lock member 13, which has 45 a member 14, which normally projects in the lock member 15, secured at the outer side of the frame 12. This member 14 has an opening 16, through which the bolt 17 is 50 normally disposed. This bolt 17 is disposed in guide members 18 in the lock member 15, and it projects through the hollow rod 19, which is mounted for rotating in the opening 20. At one end of the lock member 15 there is another rod 21, which is mounted 55 for rotating in an opening in the other end

22 of the lock member 15. These rods 19 and 21 also have outer projections 23, which are mounted for rotating in the bearing members 24, secured to the side of the bag 60 to which the lock member 15 is secured.

Secured to the rods 19 and 21 for rotating therewith, there is a handle 25, having a hollow portion 26, in which is disposed a curved member 27, the lower end 28 of which 65 is articulated to the arm 29 of the lever 30, this lever 30 being fulcrumed at 31, to the bearing member 32, secured to the hollow handle 25, as best shown in Fig. 3 of the drawings. To the other arm 33 of the lever 70 30, there is secured a member 34, this member being also secured at 35 to the bolt 17.

To the upper portion of the member 27 there is secured a connecting member 36, this connecting member 36 having laterally 75 extending pins 37, and having its end 38 engaging the spring 39, the end 40 of the said spring pressing against the stop 41, secured in the hollow handle 25. Projecting through the opening 42 in the handle member 35, there is a trigger member 43, this trigger member 43 having curved arms 44, for engaging the pins 37. It will therefore be seen that when the trigger member 43 is held against the handle 25, as shown in Fig. 80 1 of the drawings, the member 36 and the member 27 will be pressed by the spring 39 outward, and downward, to press the member 34 inward, by means of the lever 30, and as the bolt 17 is secured to this member 34, 85 the bolt will be moved into the opening 16 in the member 14, thereby holding the lock member 13 in position relatively to the lock member 15, as shown in Fig. 6 of the drawings.

As the trigger 43 is disposed in a 90 convenient place, where it may be inclosed by the hand of the person who carries the bag 10, by its handle 25, it will be impossible for any person to open the bag, without first disengaging the hand of the person 95 who is carrying the bag. The bag may be unlocked by moving the trigger to the position shown by the dotted lines in Fig. 2 of the drawings.

Having thus described my invention, I 100 claim as new and desire to secure by Letters Patent:

1. A bag having a lock, and a hollow handle, a lever fulcrumed adjacent the connection of the hollow handle with the body 110 of the bag, a member in the handle engaging one arm of the lever, and means by

which the other arm of the lever is adapted for operating the lock.

2. A bag having a lock and a hollow handle, a lever fulcrumed adjacent the connection of the hollow handle with the body of the bag, a member in the handle engaging one arm of the lever, means by which the other arm of the lever is adapted for operating the lock, and resilient means for holding the member yieldingly in a predetermined position.

3. A bag having a lock and a hollow handle with an opening, a member in the handle, means by which the member is adapted for operating the lock, a trigger extending through the opening in the handle and having a curved arm, means with a pin secured to the member and with the pin engaged by the curved arm, and a spring in the handle for engaging the second means.

4. A bag having a lock and a hollow handle, there being an opening from the interior of the handle through its outer surface, a member in the handle, means by which the member is adapted for operating the lock, a trigger member articulated to the first member and extending through the opening, the trigger member having sides for engaging the outer side of the handle, and a spring in the handle for engaging the first member to hold the first member in a predetermined position relatively to the handle.

5. A bag having a lock member, two rods mounted for turning on the lock member, one of the rods being hollow, a bolt for the

lock member, a hollow handle secured to the rods for rotating therewith, a member in the hollow handle, means by which the member is adapted for operating the bolt, means for operating the last-mentioned member, and another member on the bag for engagement by the bolt.

6. A bag having a lock member, two rods mounted for turning on the lock member, one of the rods being hollow, a bolt for the lock member, a hollow handle secured to the rods for rotating therewith, a member in the hollow handle, a lever to which the last member is articulated, means connecting the lever with the bolt for operating the latter, and another lock member on the bag for engagement by the bolt.

7. A bag having a lock member, two rods mounted for turning on the lock member, one of the rods being hollow, a bolt for the lock member, a hollow handle secured to the rods for rotating therewith, a member in the hollow handle, a lever to which the last member is articulated, means connecting the lever with the bolt for operating the latter, another lock member on the bag for engagement with the bolt, and a spring for holding the member and the hollow handle yieldingly in a predetermined position.

In testimony whereof I have signed my name to this specification in the presence of two subscribing witnesses.

JOHAN PARTMANN.
